DESIGN FOR A SHOE SOLE

Robert Herron, Revere, Mass.

Application May 12, 1943, Serial No. 110,186

Term of patent 14 years

To all whom it may concern:

Be it known that I, Robert Herron, a citizen of the United States, residing at 49 Howard Street, Revere, in the county of Suffolk and State of Massachusetts, have invented a new, original, and ornamental Design for a Shoe Sole, of which the following is a specification, reference being had to the accompanying drawing, forming a part thereof, in which Fig. 1 is a perspective view of a shoe sole, and Fig. 2 is a cross-sectional view thereof taken along the line 2-2 of Fig. 1, showing my new design.

I claim:

The ornamental design for a shoe sole, substantially as shown.

ROBERT HERRON.
